(57) CLAIM

The ornamental design for a miniature architectural model as shown and described.

DESCRIPTION

FIG. 1 is a top, right, front perspective view of a miniature architectural model showing the new design;

FIG. 2 is a bottom, left, front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the pictures show portions of the miniature architectural model, which form no part of the claimed design.
